UNITED STATES PATENT OFFICE.

CHARLES W. FOWLER AND ANTON O. NEPIL, OF DES MOINES, IOWA.

BOILER-FURNACE.

SPECIFICATION forming part of Letters Patent No. 330,885, dated November 24, 1885.

Application filed December 29, 1884. Serial No. 151,514. (No model.)

To all whom it may concern:

Be it known that we, CHARLES W. FOWLER and ANTON O. NEPIL, of Des Moines, in the county of Polk and State of Iowa, have invented 5 an Improved Boiler - Furnace, of which the following is a specification.

Our object is to reduce the cost of constructing, combining, and maintaining in order all the parts of a boiler-furnace; to prevent the 10 annoyances and loss incident to the generation and escape of gas, smoke, and soot; to increase the water-heating surface; to diminish the minimum of fuel required, and to augment the maximum of heat and power produced from 15 any given quantity of fuel.

Heretofore an annular boiler-section having vertical tubes in its upper portion and adapted to be used as a fire-chamber has been inclosed in a second annular boiler-section, and a third 20 annular boiler-section placed over the two concentric sections, and a fuel-magazine extended through the top section and into the inner lower section, and the three sections connected by means of tubes to produce a circulation of 25 water and steam, and a grate and wall combined with the three boiler-sections thus constructed and connected to produce a boiler-furnace; but in no instance have two separate and distinct boiler-sections been formed as 30 contemplated by our invention, which consists in the construction and combination of two cylindrical boiler-sections of peculiar shape that are specially adapted to produce, in combination with each other and a fuel-magazine, 35 three distinct combustion - chambers, within which three chambers the products of combustion will be more effectually utilized than heretofore, and by means of which chambers an increased area of water-heating surface is produced without increasing the size and cost of 40 the complete boiler and furnace.

Figure 1 of our accompanying drawings is a vertical section of our boiler-furnace. Fig. 2 is a transverse section at the point of elevation indicated by dotted line X X in Fig. 1.

Jointly considered these figures clearly illustrate the construction and operation of our complete invention.

A represents the outside wall of the furnace, 50 which may be made of brick or plate metal, and vary in size as desired.

B is the lower section of our boiler, support-

ed upon the furnace-wall. It is composed of a cylinder, B², made of boiler-iron, and three concentric plates, B³, B⁴, and B⁵, that vary in 55 diameter. These concentric plates are connected by means of ring-shaped plates C, C', and C'', that have flanged edges that overlap the plates, and can be readily riveted fast in a common way to produce a fire-box, No. 1, and 60 an ash-box in the lower portion, and a combustion-chamber, No. 2, in its upper portion. A series of open-ended tubes, D, are fixed to the ring-shaped plates to extend through the boiler-section and double wall of the fire-box 65 thus formed. A second series of open-ended tubes, D², extend through the upper portion of the same boiler-section to establish communication between the chambers Nos. 1 and 2 and a chamber, No. 3, at the top of the tubes 70 and the space outside of the boiler.

F is the upper boiler-section, composed of a cylinder-plate, G, a short concentric plate, G', a bottom, H, a top, J, and an open-ended cylinder, K, that is fixed in the center of the top 75 and bottom plates to form an opening for the introduction of a fuel-magazine, L, that extends through the upper portion, F, of the boiler and down into the combustion-chamber No. 2, so that its lower open end will terminate near 80 the fire-chamber No. 1, as shown in Fig. 1. This magazine is fastened to the upper boiler-section by means of screw-bolts or in any suitable way, so that it will be detachably connected and suspended within the boiler. 85

N N are tubes attached to the upper and lower boiler-sections to conduct water from the upper to the lower and to circulate water and steam in the complete boiler.

R represents a grate that may vary in form 90 as desired, supported in the lower end of the complete boiler by means of bars fixed to the boiler or in any suitable way.

S is an ash-box and air-chamber fixed to the lower end of the boiler and under the grate to 95 receive the ashes that fall through the grate and to supply air for the fire above the grate.

T is a soot-chamber on the outside of the plate B³ and the ash-box, into which ashes, soot, or any solid matter that may be drawn 100 through the tubes D and D² will drop, and from whence it can be readily removed through a door on the outside furnace-wall.

In the practical operation of our boiler-fur-

nace thus constructed the fire is started upon the grate, which is accessible through doors in the outside walls and the lower boiler-section, and fuel is then supplied to the fire through 5 the removable top of the suspended fuel-magazine in a common way. The products of combustion will rise and fill the annular chamber that extends above the fire-chamber, and from thence press downward to pass over the burning fuel to aid combustion, and up through the short inner series of tubes, the annular chamber No. 3 at their top ends, and from thence downward through the outer series of tubes into the annular space that exists between the 10 boiler and the outside wall, in which annular space they will rise to escape through a smoke-flue or chimney connected with the upper portion of the outside wall. The boiler-surface, consisting of the walls of the chambers Nos. 1 and 2, the series of tubes D and D², and the 15 annular chamber No. 3 at their top ends, the tubes N, and the outside surface of the vertical portion of the entire boiler, is thus constantly enveloped by the products of combustion, and 20 absorbs substantially all the heat that is generated in the furnace, and utilizes the heat in 25

producing steam and power. Cold air is admitted through an automatic register into the ash-box under the grate, where it becomes heated and ascends through the grate and fuel 30 to promote combustion.

We claim as our invention—

1. The improved boiler-furnace composed of an outer wall, A, a boiler-section and furnace-chamber, B, a boiler-section, F G G' H J 35 K, a fuel-magazine, L, tubes N, a grate, and an air and ash box, substantially as shown and described, to produce chambers Nos. 1 and 2 and 3, and to operate in the manner set forth, for the purposes specified.

2. The combination of the boiler - section composed of concentric walls B², B³, B⁴, and B⁵, the ring-shaped plates C C' C², and the boiler-section composed of the concentric plates G and G', a bottom, H, a top, J, and an open-ended cylinder, K, substantially as shown and 40 described, for the purposes stated.
